FIG. 5 is a second side view of the ambulation aid of FIG. 1. FIG. 6 is a top view of the ambulation aid of FIG. 1. FIG. 7 is a bottom view of the ambulation aid of FIG. 1. FIG. 8 is a second isometric view of the ambulation aid of FIG. 1. FIG. 9 is a first isometric view of an ambulation aid in a folded configuration. FIG. 10 is a rear view of the ambulation aid of FIG. 9. FIG. 11 is a front view of the ambulation aid of FIG. 9. FIG. 12 is a first side view of the ambulation aid of FIG. 9. FIG. 13 is a second side view of the ambulation aid of FIG. 9. FIG. 14 is a top view of the ambulation aid of FIG. 9. FIG. 15 is a bottom view of the ambulation aid of FIG. 9. FIG. 16 is a second isometric view of the ambulation aid of FIG. 9. FIG. 17 is a first isometric view of an ambulation aid showing a storage compartment in a closed position, a tray in a stored position and a seat in a stored position. FIG. 18 is a rear view of the ambulation aid of FIG. 17. FIG. 19 is a front view of the ambulation aid of FIG. 17. FIG. 20 is a first side view of the ambulation aid of FIG. 17. FIG. 21 is a second side view of the ambulation aid of FIG. 17. FIG. 22 is a top view of the ambulation aid of FIG. 17. FIG. 23 is a bottom view of the ambulation aid of FIG. 17. FIG. 24 is a second isometric view of the ambulation aid of FIG. 17. FIG. 25 is a first isometric view of an ambulation aid showing a storage compartment in a closed position, a tray in a stored position and a seat in a non-stored position. FIG. 26 is a rear view of the ambulation aid of FIG. 25.

FIG. 27 is a front view of the ambulation aid of FIG. 25. FIG. 28 is a first side view of the ambulation aid of FIG. 25. FIG. 29 is a second side view of the ambulation aid of FIG. 25. FIG. 30 is a top view of the ambulation aid of FIG. 25. FIG. 31 is a bottom view of the ambulation aid of FIG. 25. FIG. 32 is a second isometric view of the ambulation aid of FIG. 25. FIG. 33 is a first isometric view of an ambulation aid showing a storage compartment in an open position, a tray in a stored position and a seat in a stored position. FIG. 34 is a rear view of the ambulation aid of FIG. 33. FIG. 35 is a front view of the ambulation aid of FIG. 33. FIG. 36 is a first side view of the ambulation aid of FIG. 33. FIG. 37 is a second side view of the ambulation aid of FIG. 33. FIG. 38 is a top view of the ambulation aid of FIG. 33. FIG. 39 is a bottom view of the ambulation aid of FIG. 33. FIG. 40 is a second isometric view of the ambulation aid of FIG. 33. FIG. 41 is a first isometric view of an ambulation aid showing a storage compartment in a closed position, a tray in a non-stored position and a seat in a stored position. FIG. 42 is a rear view of the ambulation aid of FIG. 41. FIG. 43 is a front view of the ambulation aid of FIG. 41. FIG. 44 is a first side view of the ambulation aid of FIG. 41. FIG. 45 is a second side view of the ambulation aid of FIG. 41. FIG. 46 is a top view of the ambulation aid of FIG. 41. FIG. 47 is a bottom view of the ambulation aid of FIG. 41; and, FIG. 48 is a second isometric view of the ambulation aid of FIG. 41. The features shown in broken lines represent structural components of the ambulation aid, for example. The features shown in broken lines form no part of the claimed design. The features shown in dot/dashed lines represent contouring of the ambulation aid, for example. The features shown in dot/dashed lines form no part of the claimed design.
